US0D1038430S

(12) **United States Design Patent** (10) **Patent No.:** **US D1,038,430 S**
(45) **Date of Patent:** **** Aug. 6, 2024**

(54) **APPARATUS FOR MEDICAL OR
LABORATORY DIAGNOSIS**

(71) Applicant: **Eppendorf SE**, Hamburg (DE)

(72) Inventors: **Frank Zhao**, Shanghai (CN); **Terry Sha**, Shanghai (CN); **Aljay Jiang**, Shanghai (CN); **Kaiyang Fan**, Shanghai (CN)

(73) Assignee: **EPPENDORF SE**, Hamburg (DE)

(**) Term: **15 Years**

(21) Appl. No.: **35/516,178**

(22) Filed: **Mar. 16, 2022**

(80) **Hague Agreement Data**

Int. Filing Date: **Mar. 16, 2022**

Int. Reg. No.: **DM/220317**

Int. Reg. Date: **Mar. 16, 2022**

Int. Reg. Pub. Date: **May 6, 2022**

(51) **LOC (14) Cl.** **24-02**

(52) **U.S. Cl.**

USPC **D24/216**

(58) **Field of Classification Search**

(57) **CLAIM**

The ornamental design for apparatus for medical or laboratory diagnosis, as shown and described.

DESCRIPTION

1. Apparatus for medical or laboratory diagnosis
  2. Apparatus for medical or laboratory diagnosis
  3. Apparatus for medical or laboratory diagnosis
  4. Apparatus for medical or laboratory diagnosis
- 2.1 : Bottom
2.2 : Rear
2.3 : Front
2.4 : Right
2.5 : Top, Front, Right Perspective
2.6 : Left
2.7 : Top
4.1 : Bottom
4.2 : Rear
4.3 : Front

(Continued)

- 4.4 : Right
 4.5 : Top, Front, Right Perspective
 4.6 : Left
 4.7 : Top
